UNITED STATES PATENT OFFICE.

WILHELM PAPE, OF CHARLOTTENBURG, GERMANY, ASSIGNOR TO GENERAL ELECTRIC COMPANY, A CORPORATION OF NEW YORK.

SAFETY DEVICE FOR PRIME MOVERS, ESPECIALLY FOR STEAM TURBINES.

Application filed April 12, 1922. Serial No. 555,248.

To all whom it may concern:

Be it known that I, WILHELM PAPE, a citizen of the German Republic, residing at 69 Niebuhrstrasse, in the city of Charlottenburg, Province of Brandenburg, State of Prussia, Germany, have invented a new and useful Safety Device for Prime Movers, Especially for Steam Turbines (for which I have filed an application in Germany 10 June 1, 1917), of which the following is a specification.

My invention relates to an improved safety device for prime movers, more especially for steam turbines. It is common 15 practice to provide steam turbines with an emergency valve mechanism to keep them from racing. Such mechanisms in most cases comprise a valve biased toward closed position, a locking device or catch for holding it open against the biasing force, and an emergency governor which releases the locking device or catch when the speed of 20 the turbine exceeds a certain number of revolutions, to permit the valve to close, 25 there being suitable means for transmitting power from the emergency governor to the locking device or catch.

It has been proven by experience that such devices are not sufficiently safe. If 30 any one member of the safety device becomes clogged by dirt, causing a jamming, then the whole device is put out of commission, with no means left to prohibit the engine from racing. The fact that all parts of 35 the safety device are at rest during the normal running of the engine makes it more subject to jamming. This latter evil is not overcome by operating the mechanism frequently by hand, as by this means the 40 emergency governor is not worked. This latter does not change its position until the engine exceeds the speed for which the governor is set, that is not until the engine is actually racing.

The object of my invention is to provide 45 an improved structure and arrangement whereby I obtain a higher degree of safety from racing than has heretofore been obtained. I obtain this object by introducing 50 an additional safety device, which is also influenced by the speed of the engine, and which actuates either the same or a second quick closing valve. In this case two separate locking devices or catches may be oper-

ated by either the same or by an additional 55 emergency governor; or an additional valuable improvement may be obtained by using the standard engine governor, instead of using an additional emergency governor. This latter improvement will cause the engine to be under the influence of a governor which is always in motion and always under control of the engineer. This combination will act if the engine surpasses the speed limit and will be independent of the original 60 emergency governor. Any damage or dirt interfering with the operation of a standard governor will instantly cause the engine to run irregularly by causing it to alternately speed up and slow down and can always be 65 adjusted in time before the governor would give out completely.

In the drawing the figure is a diagrammatic view of an elastic fluid turbine having a governing mechanism embodying my invention.

Referring to the drawing, 1 indicates a known type of emergency governor carried by the shaft 1^a of the turbine T. It comprises a plunger 1^b which is normally held 80 within the confines of the shaft by a spring 1^c and is thrown outward by centrifugal force in case of excess speed to engage a trip finger 1^d. Trip finger 1^d is connected to the catch or locking device 2 of a quick 85 closing emergency valve 2^a by means of a rod 3. Valve 2^a is biased to closed position by a spring 2^b and is adapted to be held open against the biasing force by catch 2, the arrangement being such that in case of 90 excess speed plunger 1^b is thrown out by centrifugal force to strike trip finger 1^d thereby pulling on rod 3 and moving catch 2 to release valve 2^a and permit it to close. This is a known arrangement of emergency 95 valve gear and is to be taken as typical of any suitable apparatus of this type.

The turbine is provided with a speed governor 4 having its governor lever 4^a connected to the pilot valve 4^b of a servomotor, the connections including a usual form of follow-up connections. The piston 4^c of the servomotor is connected to a regulating valve mechanism 4^d which controls the admission of elastic fluid through conduit 4^e to the turbine. The speed governor, servomotor and valve mechanism may be 100 of any suitable type, the arrangement 105

illustrated being a known one, the operation of which is well understood.

In conduit 4^e is a valve 5 having its stem connected to a piston 6 located in a cylinder 6^a. Valve 5 is biased to closed position by a spring 6^b. Valve 5 is normally held open against the action of spring 6^b by fluid pressure admitted to cylinder 6^a beneath piston 6 by a pipe 7. Pipe 7 connects to a valve 10 casing 7^a in which is a valve 8 adapted to connect pipe 7 either to a source of fluid pressure represented by pipe 8^b or to a region of lower pressure represented by discharge pipe 10. The stem 9 of valve 8 is 15 connected to or forms a continuation of the stem of pilot valve 4^b. In pipe 7 is a valve 11 adapted to be operated by hand and arranged to disconnect pipe 7 from valve casing 7^a, and hence the source of fluid pressure supply, and connect it to atmosphere or other region of lower pressure.

During normal operation, the parts are in the positions shown in the drawing, valves 2^a and 5 being held open and governor 4 operating valve mechanism 4^d in the well understood manner to maintain the speed of the turbine constant. Under these operating conditions valve 8 stands below the end of pipe 7, giving free access of fluid 20 pressure from pipe 8^b through pipe 7 to cylinder 6^a, whereby valve 5 is held open. The arrangement is such that with increase 25 in speed governor 4 raises pilot valve 4^b whereby motive fluid will be admitted 30 above piston 4^c moving it downward and valve mechanism 4^d toward closed position so as to admit less motive fluid to the turbine. With decrease in speed the operation 35 is the same except that it is in the opposite direction. In case the turbine starts racing, speed governor 4 in moving the pilot valve 40 will move valve 8 upward to a point beyond the end of pipe 7, thereby cutting off communication between pipe 7 and pipe 8^b and connecting pipe 7 to discharge pipe 10. The pressure under piston 6 will escape immediately 45 through pipes 7 and 10 whereupon spring 6^b will close valve 5. At the same time the emergency governor 1 will effect the closing of valve 2^a and the servomotor will effect the closing of valve mechanism 4^d.

Preferably as a source of pressure for 50 pipe 8^b, I utilize the oil pressure of the forced feed lubricating system for the turbine. With this arrangement, in case the pressure of the lubricating system fails valve 5 will be closed and the turbine thus shut down.

By turning by hand the three-way valve 55 or cock 11 located in pipe 7, this pipe may be opened to the atmosphere, permitting the pressure under piston 6 to escape and valve 5 to close.

It will be seen that this whole second

safety device is created by the simple addition of pipe 7 and by adding a new bonnet to piston 6. This small addition to the customary arrangement can be made at small expense.

With the above-described arrangement, if the engine starts racing not only are the usual emergency valve 2^a and the regulating valve 4^d closed but in addition the valve 5 is closed. In this way the elastic fluid is 75 safely cut off even should the emergency valve refuse to work, a thing which may be caused by dirt clogging the air piston, by leaky valve seats or other causes.

The emergency valve 5 gets into action 80 every time the engine is started or stopped. The main governor 4 and the auxiliary piston valve 8 are always in action and in constant motion, as long as the engine is running, so that these parts are under continuous observation and are unlikely to fail. By the use of hydraulic power transmission for valve 5, auxiliary apparatus, such as air cushions for braking the impact of the quick closing valve, is unnecessary because the 90 liquid itself while being displaced from underneath the piston acts as a dashpot to effect a gradual closing of the valve.

In accordance with the provisions of the 95 patent statutes, I have described the principle of operation of my invention, together with the apparatus which I now consider to represent the best embodiment thereof, but I desire to have it understood that the apparatus shown is only illustrative and 100 that the invention may be carried out by other means.

What I claim as new and desire to secure by Letters Patent of the United States, is:

1. The combination with a prime mover, 105 of a regulating valve controlling the admission of elastic fluid thereto, a speed governor for the regulating valve, an emergency valve controlling the admission of elastic fluid to the prime mover, and means 110 operated by said speed governor for effecting the closing of the emergency valve.

2. The combination with a prime mover, 115 of a regulating valve controlling the admission of elastic fluid thereto, a speed governor for the regulating valve, an emergency valve controlling the admission of elastic fluid to the prime mover, means biasing it to closed position, fluid-operated means for holding it open against the biasing force, and means operated by said speed governor for relieving the pressure on said fluid-operated means when the speed reaches a predetermined high rate.

3. The combination with a prime mover 125 having a fluid admission conduit, of a regulating valve mechanism in said conduit, a speed governor, a servo-motor through which the speed governor controls said regulating valve, a quick closing valve in 130

said conduit, an emergency governor for effecting the closing of it, a second quick closing valve in said conduit, and means actuated by the speed of the prime mover for effecting the closing of said second quick closing valve.

4. The combination with a prime mover having a fluid admission conduit, of a regulating valve mechanism in said conduit, 10 a speed governor, a servo-motor through which the speed governor controls said regulating valve, a quick closing valve in said conduit, an emergency governor for effecting the closing of it, a second quick closing 15 valve in said conduit, means biasing it toward closed position, fluid-operated means for holding it open against said biasing

means, and speed governor-operated means controlling the fluid-operated means.

5. The combination with a prime mover 20 having a fluid admission conduit, of a regulating valve mechanism in said conduit, a speed governor for operating it, a quick closing valve in said conduit, fluid pressure actuated means for holding it open, and 25 means operated by said speed governor which at normal speed connects said fluid pressure-actuated means to a source of fluid pressure and at abnormal speed connects it to a region of lower pressure.

In witness whereof, I have hereunto set my hand this twenty-second day of March, 1922.

WILHELM PAPE.
